CIRCUIT INTERRUPTER

Albert P. Strom, Forest Hills, Pa., assignor to
Westinghouse Electric Corporation, East Pittsburgh, Pa., a corporation of Pennsylvania

Application September 20, 1944, Serial No. 554,898

8 Claims. (Cl. 200—150)

1

This invention relates to circuit interrupters in general and, more particularly, to arc extinguishing structures therefor.

A general object of my invention is to provide an improved circuit interrupter which will more effectively interrupt the circuit therethrough than has been achieved heretofore.

A more specific object is to provide an improved circuit interrupter in which an arc is drawn through an orifice and rotated therein while being simultaneously subjected to a fluid blast through the orifice. The fluid blast directed through the orifice may be either a gas or an insulating arc extinguishing liquid such as oil.

Another object is to provide an improved circuit interrupter in which a pair of relatively movable ring-shaped contacts are positioned on opposite sides of an orifice between which an arc is established. Preferably the arc is rotated around the pair of cooperable ring-shaped contacts while being subjected to a fluid blast passing through the orifice.

Another object is to provide an improved circuit interrupter having an improved orifice construction in which one of the cooperable contacts has an insulating fluid directing member associated therewith to symmetrically guide the fluid blast through the orifice about the contact. Preferably the fluid directing member at least partially extends within the orifice to cooperate with the walls of the orifice so that the point of maximum restriction through the orifice is closely adjacent to said contact having the fluid directing member associated therewith.

Another object is to provide an improved circuit interrupter having an improved orifice construction in which an arc drawn through the orifice is rotated therein. Preferably coil means are utilized to create a magnetic field in the vicinity of the orifice, which coil means are short-circuited in the closed circuit position of the interrupter.

Another object is to provide an improved circuit interrupter of the rotating arc type in which improved constructional details in the contact structure are employed to bring about improved and more economical operation.

Another object is to provide an improved circuit interrupter in which an arc is drawn through an orifice and subjected to a flow of liquid passing through the orifice. I provide means for adding static superimposed pressure on both sides of the orifice. Preferably the means for furnishing the static superimposed pressure comprises a gaseous region disposed above the liquid

2

level which is raised to an elevated pressure. Also preferably the arc drawn through the orifice is simultaneously rotated therein while being subjected to the liquid blast passing through the orifice.

Further objects and advantages will readily become apparent upon a reading of the following specification taken in conjunction with the drawings, in which:

10 Fig. 1 is an elevational view, partially in section, of a circuit interrupter embodying my invention, the parts being shown in the closed circuit position;

15 Fig. 2 is an enlarged vertical sectional view through the left-hand arc extinguishing unit of Fig. 1, the parts also being shown in the closed circuit position;

20 Fig. 3 is an enlarged fragmentary vertical sectional view of the upper portion of the arc extinguishing unit shown in Fig. 2, the parts being shown in the fully open circuit position of the interrupter;

Fig. 4 is a sectional view taken along the line IV—IV of Fig. 2;

25 Fig. 5 is a sectional view taken along the line V—V of Fig. 3;

Fig. 6 is a vertical sectional view through an arc extinguishing unit of modified construction embodying my invention, the parts being shown in the closed circuit position; and

30 Fig. 7 is a sectional view taken along the line VII—VII of Fig. 6.

Referring to the drawings, and more particularly to Fig. 1 thereof, the reference numeral 1 designates a tank filled to the level 2 with a suitable arc extinguishing fluid 3, in this instance circuit breaker oil. Depending from the cover 4 of the tank 1 are two insulating bushings 5, 6 through which extend terminal studs 7, 8. The terminal studs 7, 8 threadedly secure in position two arc extinguishing units 9 of identical construction which are electrically interconnected in the closed circuit position, as shown in Fig. 1 by a conducting bridging bar 10 reciprocally actuated in a vertical direction by an insulating operating rod 11 actuated by suitable mechanism not shown. The left-hand arc extinguishing unit 9 is more clearly illustrated in Figs. 2—5, inclusive.

Referring more particularly to Fig. 2, the reference numeral 13 designates a contact foot threadedly secured to the terminal stud 7 and to which is rigidly secured an annular stationary contact 14. The annular stationary contact 14 is preferably hollow having ports 15 disposed at its upper end. The upper portion of the

annular stationary contact 14 has a stud portion 16 which passes through a plate portion 17 integrally formed with the contact foot 13. Nuts 18 threadedly secured on the stud portion 16 rigidly secure the stationary contact 14 in position.

The plate portion 17 of the contact foot 13 closes the upper end of an insulating casing 19 which is secured to the contact foot 13 by suitable fastening means in this instance comprising bolts 20. The lower end of the casing 19 is closed by a metallic plate 21 rigidly secured in place by bolts 22.

Cooperable with the annular stationary contact 14 is a movable contact 23 having a ring-shaped arcing portion 24 (Fig. 3), in this instance comprising a metallic disc composed of a suitable arc resisting material. The movable contact 23 also has an annular contacting portion 25, in this instance comprising a brass sleeve fixedly secured to the movable contact 23 by pins 26, as more clearly shown in Fig. 3. The brass sleeve is slotted at 27 to render it resilient thus forming the fingers 25. Also the annular stationary contact 14 is slotted at 28 so that in the closed circuit position of the interrupter, as shown in Fig. 2, when the annular contacting portion 25 engages the annular stationary contact 14 there will be formed resilient contact pressure between the two.

Inserted into the movable contact 23, which is preferably made of copper, is a steel stud 29 which serves the function of holding in position the ring-shaped contact 24 and an insulating conically-shaped fluid directing member 30, more clearly shown in Fig. 3. The fluid directing member 30 symmetrically guides the fluid blast, in this instance oil, adjacent the ring-shaped contact 24 during the opening operation. It also, in addition to preventing the arc from lingering in the center of the orifice, fills up the dead spot which is associated with a radially converging fluid flow.

Preferably I employ means forming an orifice adjacent the point of contact separation. In this instance the means comprises a suitably shaped annular member 31 having a configuration shown in Fig. 3 which rests upon an insulating sleeve 32 also disposed in the interior of the casing 19. Movable within the sleeve 32, which forms a piston chamber, is an insulating piston 33 actuated by piston rods 34 which pass through apertures 35 formed in the plate 21. The lower ends of the piston rods 34 are threaded and cooperate with nuts 36 to secure the lower ends of the piston rods 34 to a metallic plate 37 having an aperture 38 formed therein.

Disposed between the plate 21 and the plate 37 is a compression spring 39 which serves the function of biasing the piston rods 34 and hence the piston 33 in a downward direction as viewed in Fig. 2. The downward movement of the piston 33 is determined by an upstanding ring-shaped portion 40 integrally formed with the metallic plate 21.

The movable contact 23 has two flanges 41, 42 rigidly secured thereto. The movable contact 23 passes through an aperture 43 provided in the plate 21 and has a flange portion 44 formed at its lower end which serves as a lower seat for a compression spring 45 which serves the function of biasing the movable contact 23 downwardly towards its full open circuit position as shown in Fig. 3, the flange 42 striking the

plate 21 in the full open circuit position of the movable contact 23.

The bridging bar 10 has a movable disconnect contact 46 associated therewith which moves in a bore 47 provided in the extremity 48 of the bridging bar 10. A smaller bore 49 in registration with the bore 47 contains a compression spring 50 which biases the movable disconnect contact 46 upwardly until the nuts 51 strike the lower portion 52 of the extremity 48. The nuts 51 secure a flexible conductor 53 to the movable disconnect contact 46, the other end of the flexible conductor 53 being secured by a bolt 54 to the bridging bar 10.

Thus in the closed circuit position of the interrupter the extremity 48 of the conducting bridging bar 10 maintains the plate 37 in its raised position, thereby compressing the compression spring 39. Also the movable disconnect contact 46 seated on a shoulder 55 of the extremity 48 forces the movable contact 23 upwardly against the downward biasing action exerted by the compression spring 45.

From the above description it will be apparent that in the closed circuit position of the interrupter as shown in Figs. 1 and 2, the electrical circuit therethrough comprises terminal stud 7, contact foot 13, plate portion 17 integrally formed with contact foot 13, annular stationary contact 14, annular contacting portion 25 of movable contact 23, movable contact 23 to movable disconnect contact 46, through the flexible conductor 53 and through the conducting bridging bar 10 to the other arc extinguishing unit 9. The electrical circuit extends through the right-hand arc extinguishing unit 9 in a manner identical to its passage through the left-hand arc extinguishing unit 9.

An insulating conduit 56 cooperates with metallic elbows, 57, 58, the latter threadedly secured in the walls of the casing 19 to form intercommunication between the region 59 below the piston 33 and the region 60 adjacent the annular stationary contact 14. Preferably exhaust ports 61 are provided through the walls of the casing 19 and also through the insulating sleeve 32.

Fixed to the annular stationary contact 14 is a spider 62 which is threadedly secured to a sleeve-shaped member 63 composed of a suitable magnetic material, in this instance iron. If desired, set screws 64 may be employed after the spider 62 has been threadedly secured in place to the magnetic yoke member 63. Coil means, in this instance comprising a coil 65, is employed to provide a radial magnetic field in the vicinity of the separated contacts so that the arc 66 (Fig. 3) established between the ring-shaped contact 24 and a ring-shaped stationary arcing contact 67 may be rotated therearound. One terminal of the coil 65 is electrically connected at 68 (Fig. 3) to the magnetic yoke 63 and hence through the spider 62 to the stationary contact 14. The other end of the coil 65 is connected to a brass ring coil terminal 69 which is electrically connected by screws 70 to the stationary ring-shaped arcing contact 67, which is disposed intermediate the annular stationary contact 14 and the orifice 71 on a first side of said orifice 71.

Threadedly secured to the magnetic yoke 63 is a ring-shaped member 72 composed preferably of nonmagnetic metal or insulating material. The magnetic yoke member 63 extends some

distance beyond coil 65 toward the discharge side of the interrupter in order to intensify the radial magnetic field set up by coil 65 in the vicinity of the separated contacts.

The operation of this embodiment of my invention will now be explained. To break the electrical circuit passing through the interrupter, the operating rod 11 is moved downwardly by suitable means. This permits the compression springs 38, 45 to force the piston 33 and movable contact 23 downwardly, the movable disconnect contact 46 remaining in engagement with the flange portion 44 of the movable contact 23. As the piston 33 moves downwardly fluid, in this instance oil, is caused to pass upwardly through the conduit 58 to the region 80, downwardly through the perforations 78 provided in the spider 62 and downwardly through the orifice 71 from the first side thereof to the second side thereof.

As the annular contacting portion or fingers 25 of the movable contact 23 pass below the lower ends of the fingers 78, the fingers 25 spread out and make contacting engagement with the ring-shaped arcing contact 67. The coil 65 is now in series circuit. Further downward movement of the movable contact 23 draws an arc 66 between the ring-shaped stationary arcing contact 67 and the ring-shaped arcing portion 24 of movable contact 23 as shown in Fig. 3. Fig. 3 represents the fully open position of the contacts when the flange 42 strikes the plate 21. However, the arc 66 may have been extinguished before this fully open position is reached. Now the electric circuit extends from the stationary contact 14 through the metallic spider 62 through the magnetic yoke member 63, coil 65, brass ring terminal coil 68, screws 70, ring-shaped stationary arcing contact 67 through the arc 66 (Fig. 3) to the ring-shaped arcing contact 24. The radial magnetic field set up by the coil 65 and intensified by the magnetic structure which comprises the magnetic sleeve 63 causes a rotation of the arc 66 around the contacts 67, 24 while it is positioned within the orifice 71 and while it is being simultaneously subjected to a blast of fluid, in this instance oil, passing downwardly through the orifice 71. The result is a rapid extinction of the arc 66 and a consequent breaking of the electrical circuit passing through the interrupter.

Following the interruption of the electrical circuit the movable disconnect contact 46 separates from the movable contact 23 to insert an insulating gap into the circuit, the bridging bar 10 moving downwardly to a position indicated by the dotted line 77 of Fig. 1.

From the foregoing description it will be apparent that I have provided an improved circuit interrupter of the orifice type in which I draw an arc through the orifice and rotate said arc while it is positioned therein utilizing a radial magnetic field set up by a coil which is short-circuited in the closed circuit position of the interrupter. Preferably the point of maximum restriction through the orifice, designated by the reference numeral 71, is positioned closely adjacent to the ring-shaped arcing contact 24. The point of maximum restriction is near the discharge end of the arc so that the arc lies essentially in a region where pressure is above atmospheric pressure. This increases the di-

electric strength of the arc and improves interruption. It will also be observed that the insulating follower 30 extends partially within the orifice 71 and cooperates with the walls of the orifice in directing symmetrically the fluid flow adjacent the ring-shaped contact 24.

In the embodiment of my invention shown in Figs. 6 and 7, the arc extinguishing features adjacent the orifice 71 are the same as previously described. However, a gaseous region 80 disposed above the oil liquid level 81 is raised to an elevated static pressure which may approach the order of 350 to 400 pounds per square inch. Thus the oil which is disposed within the interrupting structure is subjected to the above static superimposed pressure caused by compressing the gas within the region 80 to the above pressure by means of the gaseous pressure supply conduit 94. The movable contact 23 is biased upwardly by a compression spring 45 and is forced to the closed position by a fork 82 integrally formed with a lever 83 pivotally mounted at 84 to a bracket 85 secured at its lower end by a bolt 86 to the casing 87. The right-hand end of the lever 83 is also bifurcated at 88 having the legs of the bifurcated portion 88 engaging a metallic sleeve 89 which surrounds an operating rod 90 which may be actuated by suitable means not disclosed. The operating rod 90 extends through a piston chamber 91 and has secured thereto a piston 92 which causes the desired circulation of oil through the orifice 71.

During the opening operation, the operating rod 90 is moved downwardly, to cause a downward movement of the piston 92 within the piston chamber 91 thereby causing the desired circulation of oil through the orifice 71 and meanwhile permitting the compression spring 45 to force the movable contact 23 upwardly drawing an arc and extinguishing the same in the manner as previously described in connection with the interrupter shown in Figs. 1-5. This embodiment of my invention is largely concerned with the maintaining of a desired static superimposed pressure above the oil level which thereby causes pressure to exist on both sides of the orifice 71. An over-pressure valve 95 limits the pressure within region 80. The result of utilizing the static superimposed pressure, which may be of the order of 400 pounds per square inch, causes increased effective operation of the interrupter.

From the foregoing description it will be apparent that I have provided an orifice type circuit interrupter in which the arc is established within an orifice and rotated therein while being simultaneously subjected to a fluid blast. By providing the above described improved constructional details the coil used for providing the radial magnetic field is short-circuited in the closed circuit position of the interrupter and hence energy dissipated through heat is consequently minimized. By utilizing static superimposed pressure, in this instance comprising a gaseous region 80 raised to a suitable high elevated static pressure, interrupting performance is increased.

Although I have shown and described specific structures, it is to be clearly understood that the same were merely for the purpose of illustration and that changes and modifications may readily be made by those skilled in the art without departing from the spirit and scope of the appended claims.

I claim as my invention:

1. In a circuit interrupter of the fluid blast type, means at least partially of insulating material defining an orifice, a pair of ring-shaped contacts positioned on opposite sides of the orifice at least in the fully open circuit position of the interrupter, means for drawing an arc through the orifice with its terminal ends disposed at the ring-shaped contacts, means for rotating the arc around the ring-shaped contacts while it is positioned within the orifice, means for forcing a blast of fluid through the orifice, and an insulating fluid directing member fixed to one of the ring-shaped contacts and extending at least partially within the orifice beyond the said one ring-shaped contact during the interruption process to symmetrically direct the fluid blast on all sides of the last-mentioned contact.

2. In a circuit interrupter of the fluid blast type, means defining an orifice, a ring-shaped contact positioned on one side of the orifice at least in the fully open circuit position of the interrupter, means for drawing an arc through the orifice with one terminal end positioned at the ring-shaped contact, an insulating conically-shaped fluid directing member projecting beyond the ring-shaped contact at least partially within the orifice during the interruption process for symmetrically guiding the fluid blast through the orifice about the ring-shaped contact, and means for rotating the terminal end of the arc around the ring-shaped contact.

3. In a circuit interrupter of the fluid blast type, means defining an orifice, a ring-shaped contact positioned on one side of the orifice at least in the fully open circuit position of the interrupter, means for drawing an arc through the orifice with one terminal end thereof positioned at the ring-shaped contact, a conically-shaped fluid directing member composed of insulating material extending beyond the ring-shaped contact at least partially within the orifice and fixed by a magnetic stud to the ring-shaped contact to symmetrically direct the fluid blast about the ring-shaped contact, and magnetic means for rotating the terminal end of the arc around the ring-shaped contact.

4. In a circuit interrupter of the fluid blast type, means defining an orifice, an annular stationary contact disposed on a first side of the orifice, a stationary ring-shaped arcing contact disposed intermediate the annular stationary contact and the orifice also on the first side of the orifice, a movable contact having a forward ring-shaped arcing portion and a rearwardly flexible sleeve-like contacting portion movable from the second side of the orifice through the orifice to the first side thereof so that in the closed circuit position of the interrupter the sleeve-like contacting portion of the movable contact makes resilient contacting engagement with the annular stationary contact, during the opening operation an arc is drawn between the forward ring-shaped arcing portion of the movable contact and the stationary ring-shaped arcing contact, the sleeve-like contacting portion spreading outwardly sufficiently enough to actually contact the stationary ring-shaped arcing contact after separation from the annular stationary contact, and radial magnetic field coil means connected between the two stationary contacts to cause rotation of the arc.

5. In a circuit interrupter of the fluid blast type, means defining an orifice, an annular stationary contact disposed on a first side of the

orifice, a stationary ring-shaped arcing contact disposed intermediate the annular stationary contact and the orifice also on the first side of the orifice, a movable contact having a forward ring-shaped arcing portion and a rearward resilient sleeve-like contacting portion movable from the second side of the orifice through the orifice to the first side thereof so that in the closed circuit position of the interrupter the sleeve-like contacting portion of the movable contact makes resilient contacting engagement with the annular stationary contact, during the opening operation an arc is drawn between the ring-shaped arcing portion of the movable contact and the stationary ring-shaped arcing contact, and coil means electrically connected between the annular stationary contact and the stationary ring-shaped arcing contact to rotate the arc around the ring-shaped arcing portion of the movable contact and the stationary ring-shaped arcing contact while it is positioned within the orifice.

6. In a circuit interrupter of the fluid blast type, means defining an orifice, an annular stationary contact disposed on a first side of the orifice, a stationary ring-shaped arcing contact disposed intermediate the annular stationary contact and the orifice also on the first side of the orifice, a radial magnetic field coil connected between the aforesaid two contacts, a movable contact having a forward ring-shaped arcing portion and a rearward annular contacting portion movable from the second side of the orifice through the orifice to the first side thereof so that in the closed circuit position of the interrupter the annular contacting portion of the movable contact makes contacting engagement with the annular stationary contact, during the opening operation an arc is drawn between the ring-shaped arcing portion of the movable contact and the stationary ring-shaped arcing contact to energize the coil and cause rotation of the arc around said contacts, and an insulating conically-shaped follower member fixed to and movable with the ring-shaped arcing portion of the movable contact to symmetrically direct the fluid blast about the movable contact during the opening operation.

7. In a circuit interrupter of the fluid blast type, means defining an orifice, a ring-shaped contact positioned on the discharge side of the orifice closely adjacent to the point of maximum restriction through the orifice at least in the open circuit position of the interrupter, means for establishing an arc within the orifice with one terminal thereof terminating at the ring-shaped contact, means for rotating the terminal end of the arc around the ring-shaped contact, and means for forcing fluid through the orifice in the direction of the ring-shaped contact.

8. In a circuit interrupter of the fluid blast type, means defining an orifice, a pair of cooperable ring-shaped contacts positioned on opposite sides of the orifice at least in the fully open circuit position of the interrupter, at least one of the ring-shaped contacts being positioned closely adjacent the point of maximum restriction on the discharge side of the orifice, means for forcing a blast of fluid through the orifice in the direction of said one ring-shaped contact, means for establishing an arc between the pair of ring-shaped contacts, and means for rotating the arc around the pair of ring-shaped contacts while it is located within the orifice.
